UNITED STATES PATENT OFFICE.

CHARLES REINISCH, OF NEWARK, NEW JERSEY.

SHOE FOR TRAVELING-BAGS.

SPECIFICATION forming part of Letters Patent No. 380,768, dated April 10, 1888.

Application filed December 19, 1887. Serial No. 258,259. (No model.)

To all whom it may concern:

Be it known that I, CHARLES REINISCH, a citizen of the United States, residing at Newark, in the county of Essex and State of New Jersey, have invented certain new and useful Improvements in Shoes for Bags; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention is designed to provide a device for protecting the lower ends of a bag-frame where they are pivoted or jointed together. The necessity for some sort of protection is manifest from the fact that in handling bags on the cars and in baggage-rooms the said ends of the frame are frequently torn apart in consequence of the rough handling to which they are subjected, particularly when they are dragged along the floor. The devices which have been used for this purpose while they have to some degree protected the frame at the point desired, still they are not readily attached to the bag.

My improved device is designed to remedy this difficulty, and to provide an improved shoe or end tip which can be secured to the bag with but comparatively little labor, and which also can be made economically.

In the accompanying sheet of drawings, in which similar letters of reference indicate corresponding parts in each of the views, Figure 1 is a side elevation of a bag to which is attached my improved shoe. Fig. 2 is a longitudinal section, enlarged, of one of the bag-joints, showing the relation of my improved shoe thereto. Figs. 3 and 4 are perspective views of the separated parts of my improved shoe, detached from the bag. Fig. 5 is a plan of the hooked portion of the said device. On Sheet 2, Fig. 6, is an end elevation of a bag, showing the relation of my improvement thereto when the bag is closed. Fig. 7 shows the relation of the same to said bag when open; and Fig. 8 is an end elevation of the shoe in its closed position, showing the hooked portion concealed behind the tip. Fig. 9 is a sectional view of the end tip-plate provided with a pin or bar projecting therefrom.

In the said views, A and A' designate the frame-sections of the bag, and B the leather portion thereof or the bag proper. Extending longitudinally through the bottom of the bag is a rod or bar, a, which is designed to strengthen the frame, and also extends through the lower ends of the frame-sections and forms the pin on which said frame-sections turn and by which they are riveted together at each of the joints.

My improved shoe, which is intended to protect the joint, consists of two portions, one of which, c, is secured to the outside of the frame-section A at the joint, and the other, d, being secured to the bottom of the bag contiguous to said joint.

For convenience of reference in description, I will call the plate or portion c the "tip" or "end tip," and the portion d the "base-plate," the device as a whole being designated as a "shoe."

As indicated in Fig. 2 more particularly, the tip is secured to the outermost frame-section, A, by the bar a, which extends through the frame-sections and is riveted on the outside of the tip, an additional screw or rivet, c', being also employed for additional security in fastening the tip to the bag-frame. As indicated in Fig. 2, the tip is so formed that when the same is secured in position to the bag-frame a space is provided between the lower portion of the tip and the frame-section to which the same is secured, and across the space thus made the bar a extends and is riveted to the outside of the tip. The object of this space is to provide room for the hooked end d' of the base-plate d to engage with that portion of the bar a which extends across said space.

The base-plate d, as shown in the drawings, consists of the body portion thereof, from the end of which projects the hooked end d', which projects into and works within the space left between the tip and the bag-frame, and is provided with a curved slot, d'', through which the bar a passes, and which permits of the requisite amount of movement of the base-plate and hooked portion thereof without the disengagement of said hooked portion from said bar. As indicated in Fig. 2, the base-plate is provided with rivet-holes d', and said base-plate is secured to the bottom of the bag by

means of the rivets d^4 , which pass through the leather b and pasteboard b' in the bottom of the bag and are riveted to a washer-plate, d^5 , on the bottom of the interior of the bag.

5 Other ways of fastening the base-plate to the bag without departing from the spirit and scope of my invention may be employed.

In those bags in which the bar a , extending through the bag, is not used, but in which the 10 joint at the end of the frame-sections is made by riveting the same together, the rivet is extended across the space between the tip and the frame-section and is riveted to the outside of the tip, as will be understood.

15 From the above description it will be seen that as the bag is opened and closed the hooked end of the base-plate moves backward and forward around the bar, thus permitting ample movement of the frame-sections, but at 20 the same time holding the base-plate in constant engagement with the said bar, so that the base-plate cannot be torn from the bottom of the bag, being held not only at the hooked end but also by the rivets b^4 .

25 The facility with which my improved shoe may be attached to the corners of the bag will be apparent to those skilled in the state of the art. When thus attached, the tip is first riveted in position, and the end d of the base-plate is 30 then hooked over the bar a , and is then riveted to the bottom of the bag. The device as above made can be readily stamped out of sheet metal and in consequence can be made very cheaply. The bar a may be formed integrally 35 with the tip and may constitute the rivet which holds the frame sections together at the joint when the said tip is cast, which is a practical method of constructing the device.

It will be noticed in Fig. 2 that the end of 40 the base-plate d is bent downward and outward at the point where the hooked portion d' meets said base-plate. Instead of thus bending down the base-plate the same may be carried straight out, as indicated in Fig. 8, so that when viewed 45 in end elevation but a little of said base-plate is seen below the edge of the tip. The end plate or tip may also be carried down to the lower edge of the base-plate, and thus conceal the same when viewed from the end and secure a better finish.

I am aware of patent, numbered 362,581, to Isaac Heller, in which is shown an end tip formed in one piece, similar to an angle-plate and secured to the bag at the joint. My improved bag-shoe or tip differs from this device 55 in being formed in two pieces secured independently to the side and bottom of the bag-joint, the tip moving with the frame-section to which it is secured, so as not to leave the 60 same projecting upwardly between the opened frame-sections, as is the case in the device above referred to. My improvement, while being formed in two portions, thereby greatly facilitating the attachment of the same to the 65 bag, is so constructed that the said portions when attached to the bag are held together,

but at the same time are free to move in their engagement when the bag is opened.

Having thus described my invention, what I claim as new is—

1. In a bag-shoe, the combination of an end tip secured to the lower end of the bag-frame, and so formed as to leave a space between said tip and the bag-frame, and provided with a bar extending across said space, a base-plate 75 secured to the bottom of said bag near the joint and provided with a hooked portion extending up into and working within the space between the tip and the bag-frame, and engaging with the bar therein, for the purposes set 80 forth.

2. In a bag-shoe, the combination, with a bag-frame, of an end tip secured to the lower end of the said bag-frame at the joint thereof, and so formed as to leave a space between said tip and the bag-frame, and provided with a bar extending across said space, and a base-plate secured to the bottom of said bag-frame near the joint, and provided with a hooked portion extending up into and working within 90 the space between the tip and the bag-frame when the bag is opened and closed and engaging with the bar therein, for the purposes set forth.

3. In a bag-shoe, the combination of a bag-frame, an end tip secured to the outside of said bag-frame at the joint and so formed as to leave a space between the same and the said bag-frame, a rivet uniting said bag-frame sections together at the joint and extending across 100 the space between the tip and said bag-frame, a base-plate secured to the bottom of the bag at the joint, and provided with a hooked portion extending up into and working within the space between the tip and the bag-frame 105 when the bag is opened and closed and engaging with the rivet or bar therein, for the purposes set forth.

4. In a bag-shoe, the combination of a bag-frame, end tips secured to the outside of said 110 frame at the joints and so formed as to leave a space between the same and the said bag-frame, a bar extending longitudinally through the bottom of the bag and the ends of the frame-sections at the joints, thus forming the rivets 115 on which said frame-sections turn, and also extending across the spaces between the end tips and the sides of the bag-frame sections at the joint, base-plates secured to the bottom of the bag near the joints, and provided with hooked 120 portions extending up into and working within the spaces between the tips and the bag-frame when the bag is opened and closed and engaging with the bar therein, for the purposes set forth.

5. A bag-shoe consisting of an end tip-plate adapted to be secured to the bottom of the side of a bag-frame at the joint, and an independent base-plate adapted to be secured to the bottom of a bag at said joint, said tip and 130 base plates being provided with engaging portions and thereby held in separable and mov-

able engagement one with the other, for the purposes set forth.

6. In combination, a bag, B, a tip, c, secured to said bag at the joint and so formed as to leave a space between the same and the bag-frame at the joint, a bar extending across the space thus made, a base-plate, d, provided with a hooked end, d', extending up into the space between the tip and the bag-frame and engaging with the bar therein, a washer-plate, d⁵, arranged in the bottom of the bag, and rivets uniting the base-plate with the washer and extending through the bottom of the bag, for the purpose set forth.

15 7. A bag-shoe having an end tip-plate pro-

vided with a pin or bar thereon, said plate being adapted to be secured to a bag-frame at the joint, and a base-plate adapted to be secured to the bottom of a bag at the joint, and provided with a bent-up end having a curved slot therein which engages with the pin on the tip-plate, for the purposes set forth.

In testimony that I claim the invention set forth above I have hereunto set my hand in the presence of two witnesses.
